Primary Examiner — W. A. Teddy Falloway(74) *Attorney, Agent, or Firm* — Rumit Ranjit Kanakia**CLAIM**

The ornamental design for a tray for snake eggs, as shown and described.

DESCRIPTION

FIG. 1 is a perspective view of a tray for snake eggs showing my new design;

FIG. 2 is a rear view thereof;

FIG. 3 is a left-side view thereof; and,

FIG. 4 is a top view thereof.

The broken lines in the drawings depict portions of the tray for snake eggs that form no part of the claimed design.

1 Claim, 4 Drawing Sheets(56)
